The ornamental design for an instrument pad endcap for a vehicle, as shown and described.

DESCRIPTION

FIG. 1 is a front left perspective view of an instrument pad endcap for a vehicle according to the present invention.

FIG. 2 is a front right perspective view of the instrument pad endcap shown in FIG. 1.

FIG. 3 is a rear right perspective view therefore.

FIG. 4 is a rear left perspective view therefore.

FIG. 5 is a font view therefore.

FIG. 6 is a rear view therefore.

FIG. 7 is a left side view therefore.

FIG. 8 is a right side view therefore.

FIG. 9 is a top view therefore.

FIG. 10 is a bottom view therefore; and,

FIG. 11 is a front left perspective view of an instrument pad endcap shown in FIGS. 1-10, but mounted on a vehicle, with the rest of the vehicle shown in de-emphasized and half-tone portions so as to illustrate environmental structure. More particularly, in FIG. 11, the inventive instrument pad endcap for a vehicle is shown within the broken line, and the elements shown outside the broken line form no part of the claimed invention, but are instead included to show environmental aspects thereof.
